DESIGN FOR A LIGHT SHADE OR SIMILAR ARTICLE

John V. Donner, Washington, Pa., assignor to
Star Mould Machine Company, Washington,
Pa., a partnership

Application August 29, 1938, Serial No. 79,616

Term of patent 7 years

To all whom it may concern:

Be it known that I, John V. Donner, a citizen
of the United States, residing at Washington,
in the county of Washington and State of Penn-
sylvania, have invented a new, original, and or-
namental Design for a Light Shade or Similar
Article, of which the following is a specification,
reference being had to the accompanying draw-
ing, forming part thereof.

In the drawing:

Fig. 1 is a side elevational view of a light shade
or similar article, showing my new design; and
Fig. 2 is an end elevational view thereof.

I claim:

The ornamental design for a light shade or
similar article, as shown.

JOHN V. DONNER.
